APPARATUS FOR THE APPLICATION OF INJECTION PRESSURE IN PRESSURE CASTING MACHINES

William H. Schwartz, Cleveland, Ohio, assignor to Lester Engineering Company, Cleveland, Ohio, a corporation of Ohio

Application December 2, 1937, Serial No. 177,723

5 Claims. (Cl. 22—68)

The present invention relates to pressure casting machines and has particular reference to apparatus for automatically controlling the rate of, sequence of, and amount of prime moving pressure applied to operate the material injection or pressure casting mechanism of such a machine. My invention is applicable to pressure casting machines used for both metallic and non-metallic materials, such as non-ferrous metals and alloys, and plastics, respectively.

The general object and nature of my invention is to so control the prime moving pressure applied to the injection cylinder of a pressure casting machine that there will result a "hammer blow" effect during the final portion of the casting stroke of the injection mechanism.

In pressure casting, there is a tendency of the material to be cast to solidify or partially freeze out, or to offer greater resistance to movement through the injection mechanism and into the mold or die cavity during such time as the material is nearing a complete occupation or filling of the mold. In the pressure casting of plastic materials especially, it is necessary that the material to be cast be moved at first slowly through the injection passages wherein it is subjected to heating, and be moved finally at a greatly increased rate into the mold. My invention, therefore, provides a process and apparatus for building up or accumulating excess pressure and then automatically applying this excess pressure to the injection mechanism, as the piston of the injection cylinder approaches the end of its pressure casting stroke.

To the accomplishment of the foregoing and related ends, said invention, then, consists of the means hereinafter fully described and particularly pointed out in the claims, the annexed drawing and the following description setting forth in detail certain means and one mode of carrying out the invention, such disclosed means and mode illustrating, however, but one of various ways in which the principle of the invention may be used.

In said annexed drawing:

The single figure of the annexed drawing is a more or less diagrammatic representation of an apparatus embodying the principle of my invention.

Now referring more particularly to the drawing, there is shown therein an injection cylinder 1 in which a piston 2 mounted upon the piston rod 3 is adapted to reciprocate. The piston rod 3 of course will be connected to the material casting cylinder (not shown) of a pressure casting machine. A conduit 4 from the head end of the

cylinder 1 and a conduit 5 from the rod end of the cylinder 1 lead to a four-way valve 6, such as is customarily employed in the installation of pressure casting machines.

A conduit 7 places the four-way valve 6 in communication with the pressure pump 8. The pressure pump 8 receives a fluid pressure medium such as oil from the reservoir 9, and is driven by an electric motor 10. The customary drain line 11 also leads from the four-way valve 6 to the reservoir 9. A pressure storage chamber or accumulator 12 is connected to the pressure supply line 7 by means of the conduit 13. The accumulator 12 is adapted to contain air or a gas such as nitrogen and to receive excess pressure delivered from the supply line 7.

A check valve 14 is located in the supply line 7 and a check valve 15 is located in the line 13. The check valves 14 and 15 are so disposed that they will permit flow only in a direction away from the pressure pump 8.

A secondary or by-pass conduit or line 16 leads from the accumulator 12 to the supply line 7 at a point beyond the check valve 14. Flow through the line 16 is controlled by the pilot valve 17. The pilot valve 17 in turn is actuated by means of pressure introduced through the line 18 to one end of its valve element 19. The opposite end of the valve element 19 is mounted against the compression spring 20 which in turn is adjustable as to compression by means of the set screw 21.

The operation of the above-described apparatus is as follows: Assuming that the injection cylinder piston 2 is ready to begin its casting stroke, or in the position as indicated in the drawing, the four-way valve 6 will be so operated as to direct pressure from the pump 8, through the line 7 through the line 4 to the head end of the cylinder 1. Assuming that for a given installation a pressure of 250 pounds per square inch will be sufficient to move the injection cylinder piston through the first and major portion of its stroke, the latter will travel on such stroke until resistance is met due to the filling of the pressure casting machine mold cavity, or due to the partial solidification or freezing out of the material. At this point, due to the fact that the fluid in the cylinder 1 and in the lines 4 and 7 cannot expand and is restricted to volume, back pressure will be built up and communicated through the line 18 to the pilot valve 17. Dependent upon the pressure adjustment setting of the pilot valve 17, the latter will be operated to place the excess pressure stored in the accumu-

lator 12 in communication, through the line 16, through the valve 6, and through the line 4 with the cylinder 1. Assuming that the accumulated pressure in the accumulator 12 is 1000 pounds per square inch, it will thus be seen that a sudden increase in pressure, having the effect of a hammer blow is delivered to the injection cylinder 1 to finally "drive the latter home."

In the next cycle of operation, the four-way valve 6 is so operated as to return the injection cylinder piston 2 to its original position, by releasing the pressure in the line 4 and applying pressure from the line 7 to the line 5. As pressure in the line 4 is decreased, the pilot valve 17 is permitted to return to its off position, as illustrated in the drawing and to thus close the bypass line 16. As the injection cylinder piston 2 reaches its return position, it is caused to dwell there for a certain period of time, while other parts of the pressure casting machine are being operated, such as the opening and closing of the dies and the feeding of the material to the mechanism. During this period, the line 7 is closed off by the valve 6, with the result that a back pressure is built up in the line 7 and communicated through the line 13, the check valve 15, to the accumulator 12, thus replenishing the supply of excess pressure, rendering it available for the next cycle of operations, or the next injection "shot."

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In a pressure casting machine, having means for injecting material in the die cavity of said machine, a pressure supply source connected to said material injecting means for operating the latter during the first portion of its stroke, and a second pressure supply source, the combination of pressure responsive means actuated by the operating pressure of said material injecting means for connecting said second pressure supply source to said material injecting means during the final portion of its stroke, and means for adjustably

regulating the pressure at which said pressure responsive means is actuated.

2. In a pressure casting machine, having means for injecting material in the die cavity of said machine, a pressure supply source connected to said material injecting means, and a pressure storage means connected to said pressure supply source, the combination of valve means for connecting said pressure storage means to said material injecting means, said valve means being actuated by the pressure delivered to said material injecting means from said pressure supply source, and means for adjustably regulating the pressure at which said valve means is actuated.

3. In a pressure casting machine, the combination of means for injecting material in the die cavity of said machine, a pressure supply source, and a pressure storage means, the combination of valve means for intermittently connecting said pressure supply source to said material injecting means, one-way valve means constantly connecting said pressure storage means to said pressure supply source, and a third valve means for connecting said pressure storage means to said material injecting means when the pressure delivered to said material injecting means exceeds a predetermined amount.

4. In a pressure casting machine, the combination of an injection cylinder, a pressure pump, an intermittently operated valve connecting said pump to said cylinder, a pressure storage tank, a check valve connecting said tank to said pump, said check valve preventing flow from said tank to said pump and a pilot valve connecting said tank to said cylinder, said pilot valve being actuated by pressure in said cylinder.

5. In a pressure casting machine having means for injecting material in the die cavity of said machine, a pressure supply source connected to said material injecting means, the combination of a pressure storage means connected to said pressure supply source, and valve means for connecting said pressure storage means to said material injecting means, said valve means being actuated by the pressure delivered to said material injecting means from said pressure supply source.
